FIG. 1 is a front view of an abrasive article having abrasive segments with shaped gullet walls according to the present design;

FIG. 2 is a rear view of FIG. 1;

FIG. 3 is a side view of FIG. 1;
FIG. 4 is a front view of a segment of abrasive article having abrasive segments with shaped gullet walls removed for clarity of disclosure of FIG. 1;

FIG. 5 is a rear view of FIG. 4;

FIG. 6 is a top view of FIG. 4;

FIG. 7 is a bottom view of FIG. 4;

FIG. 8 is a first side view of FIG. 4; and,

FIG. 9 is a second side view of FIG. 4.
